UNITED STATES PATENT OFFICE.

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA.

PROCESS OF MANUFACTURING CARLINES.

Application filed April 28, 1926. Serial No. 105,102.

My invention relates to carlines and processes of manufacturing them. It has for its principal object to produce a carline that will be stiffer and stronger than previous carlines of the same weight of metal and to facilitate the manufacture and effect greater economy of material.

The invention consists principally in a carline having a portion of its metal disposed substantially vertically and of minimum thickness along the neutral axis of the carline; and it also consists in the process of manufacturing such carline.

In the accompanying drawing, which forms part of this specification and wherein like symbols refer to like parts wherever they occur.

Fig. 1 is a face view of a blank used in producing a carline embodying my invention;

Fig. 2 is an edge view of said blank;

Fig. 3 is a side view of the carline produced from the blank shown in Figs. 1 and 2;

Fig. 4 is an end view showing the cross-sectional shape of said carline on an enlarged scale;

Fig. 5 is a face view of a blank used in producing a carline which has a maximum depth at the middle of the carline and gradually decreases in depth towards its ends;

Fig. 6 is an end view of said blank;

Fig. 7 is a side view of the carline produced from the blank shown in Figs. 5 and 6; and

Figs. 8 and 9 are enlarged vertical cross-sections taken through the carline shown in Fig. 7 on the lines 8-8 and 9-9, respectively.

Referring to Figs. 1 to 4, inclusive, of the accompanying drawing, my invention is shown in connection with a pressed metal carline A, said carline comprises a substantially inverted channel-shaped section having outstanding base flanges 10 at the lower edges of its side walls 11. As shown in the drawing, the carline A slopes downwardly from its middle towards its ends and is of substantially uniform depth throughout its length. The web 12 of the carline and the lateral base flanges 10 thereof are of uniform thickness; but the side walls 11 of said carline taper from a maximum thickness at

the top and bottom of the carline (where the parts of the cross-section are more efficient in resisting bending stresses) to a minimum thickness along the line of the neutral axis 13 thereof, where the metal is neither in tension or compression.

The carline A is produced from a metal blank comprising a flat rectangular piece of metal 14 having two grooves 15 in each of its faces that extend longitudinally of said blank and are parallel to each other and the side edges thereof. The grooves on one side of the blank 15 are disposed opposite to the grooves on the opposite side of the blank, whereby said blank is of reduced thickness along two lines parallel to each other and the side margins of the blank. The blank is preferably produced by a rolling operation and the carline shown in Fig. 3 is produced from said blank by a pressing operation, the grooves in the blank being so located that they will lie in the plane of the neutral axis of the finished carline. It is noted that this reduced thickness of the metal along the neutral axis of the carline may be produced by means of deep grooves along one side only of the blank, instead of forming shallow grooves in both sides of the blank, as shown.

The carline B shown in Fig. 7 of the accompanying drawing has a cross-sectional shape similar to the cross-sectional shape of the carline A shown in Fig. 3, the chief difference between the two carlines being that the carline A is of uniform depth; whereas the carline B is deepest at its middle and gradually decreases in depth towards its ends. The blank used to produce the carline B is shown in Figs. 5 and 6 of the accompanying drawing and comprises a rectangular piece of metal 14^a of flat section having two grooves 15^a formed in each of its side faces that extend obliquely to each other and to the parallel side margins of said blank; that is, each side of said blank is provided with two grooves that are spaced farther apart at the middle of the blank than at its ends, whereby said grooves extend lengthwise of the blank in two lines that converge from the middle of the blank towards its ends. By thus locating the grooves in the proper position and at the proper angle, the grooves are brought into a position adjacent to the neutral axis 13^a of the carline B when

said blank is pressed up to form said carline. The blank 14^a is preferably produced by heating a rectangular plate and pressing it into the shape shown.

5 The hereinbefore described carline has a cross-section adapted to resist greater stresses than previous carlines having the same weight of metal; for it places the greater portion of the metal of the carline a greater 10 distance from its neutral axis where it is more efficient in resisting bending stresses than the metal adjacent to the neutral axis. It is noted that the carline gives a maximum 15 load bearing stress with a minimum amount of metal and a minimum of weight, and it is made from a single piece of metal of uniform width, thereby minimizing the cost of material and eliminating the operation of trimming the blank to a special shape.

20 I do not wish to be limited to the type of carlines or cross-sectional shapes shown and described.

What I claim is:

1. The process of manufacturing a metal 25 carline having a portion of its metal disposed vertically which consists in forming a flat metal blank with a longitudinal groove and then pressing said blank into the shape desired for the finished carline with the 30 groove thereof disposed along the neutral axis of said carline.

2. The process of manufacturing a carline comprising a vertically disposed portion having a lateral flange which consists in rolling a rectangular plate with a longitudinal groove therein and then pressing said plate into the shape desired for the finished carline with the groove disposed along the neutral axis of said carline. 35

3. The process of manufacturing a carline 40 from a flat metal blank, which consists in providing the blank with longitudinal grooves symmetrically arranged with respect to the median line of the blank, and then pressing said blank into channel shape with 45 said grooves in the neutral axis plane thereof.

4. The process of manufacturing a metal carline having a portion of its metal disposed vertically and gradually decreasing in 50 depth from the middle of the carline toward the ends thereof which consists in forming a flat metal blank with a groove that extends obliquely to the center line of said blank at reverse angles on opposite sides of its 55 middle, and then pressing said blank into the shape desired for the finished carline with the groove in the neutral axis plane thereof.

Signed at New Kensington, Pa., this 23rd 60 day of April, 1926.

CHARLES DAVID BONSALL.
